UNITED STATES PATENT OFFICE

154,505

DESIGN FOR A SET OF COMMEMORATIVE CANDLEHOLDERS

William Niederhausen and Conrad Dallwin
Hamilton, New York, N. Y.

Application August 21, 1947, Serial No. 140,983

Term of patent 3½ years

(Cl. D48—2)

To all whom it may concern:

Be it known that we, William Niederhausen, a citizen of Germany, who has declared his intention of becoming a citizen of the United States, and Conrad Dallwin Hamilton, a citizen of the United States, each residing at New York, in the county of New York and State of New York, have invented a new, original, and ornamental Design for a Set of Commemorative Candleholders, of which the following is a specification, reference being had to the accompanying drawing, forming a part thereof.

The drawing shows perspective views of the ten commemorative candleholders, showing our new design.

The backs of the respective commemorative candleholders are substantially plain.

We claim:

The ornamental design for a set of commemorative candleholders, substantially as shown and described.

WILLIAM NIEDERHAUSEN.
CONRAD DALLWIN HAMILTON.
